Atty.

UNITED STATES PATENT OFFICE.

GEORGE E. YARGER, OF FOSTORIA, OHIO.

ROLL-PAPER HOLDER AND CUTTER.

SPECIFICATION forming part of Letters Patent No. 426,088, dated April 22, 1890.

Application filed April 27, 1889, Serial No. 308,889. (Model.)

To all whom it may concern:

Be it known that I, GEORGE E. YARGER, a citizen of the United States, residing at Fostoria, in the county of Seneca and State of Ohio, have invented certain new and useful Improvements in Roll-Paper Holders and Cutters; and I do hereby declare the following to be a full, clear, and exact description of the invention, such as will enable others skilled in the art to which it appertains to make and use the same.

This invention relates to paper holders and cutters for rolls of paper in which a gravitating transverse weighted knife bears with its edge on the roll, so that a pull on the loose end will cause the paper to be cut or torn evenly along the line of said edge, the knife or cutter descending as the roll decreases.

My invention consists in the peculiar construction and combination of parts, hereinafter particularly set forth and claimed.

In the accompanying drawings, Figure 1 represents a perspective view of the apparatus embodying my invention; Fig. 2, a vertical section on the plane of the axis of the roll; Fig. 3, a detail horizontal section through one of the standards, and Fig. 4 a detail perspective rear view of the weighted cutter.

A designates the roll of paper to be cut; B, the roller on which this paper is wound; C, the standards, having bearings c, in which turn the journals b of this roller; D, the base, to which said standards are removably fastened by screws d; E, the transverse top piece of the frame, to which said standards are similarly secured by screws e, this cross-piece being also provided with a handle E'. In the front of each standard is formed a vertical groove extending from the top of said standard about half-way to the bottom, and consisting of a narrow neck f at the front face, a wider inner part F, approximately circular in cross-section, and a bowl-shaped enlargement g at the top, where the side walls of slot f are cut away.

H designates a transverse knife or cutter, having its cutting-edge h presented obliquely outward and downward against the upper and forward part of the paper roll, so that the loose end of the latter is always before the same in the direction of rotation. At its ends this knife or cutter is provided with

weights H', arranged on its upper side in advance of the pivotal points to insure sufficient pressure on the paper. From the rear part 55 of said cutter at the bases of said weights two gudgeons extend rearward, each consisting of a rounded terminal head G, fitted to slide and turn in groove F, and a neck g' fitted to slide up and down in the slot or narrow part f of said groove. The enlargement g permits this head to be easily introduced and removed; but the narrowness of slot f prevents the dislodgment of said head at any point below the top of the standard. 60 Thus the cutter, though easily removable, will always be held securely in its position transversely to the standards. The rounded shape of said heads permits the edge h to turn downward more and more as the roll decreases, in 70 order that said edge may always be presented most effectively. The necks g' of the gudgeons are of sufficient length to allow this continued tilting.

Having thus described my invention, what 75 I claim as new, and desire to secure by Letters Patent, is—

1. In a paper holding and cutting device, a pair of standards having interior grooves or channels F and slots f, in combination with a 80 transverse knife having rearwardly-extending gudgeons consisting of the heads G, which slide up and down in grooves F, and the narrow necks g', which slide up and down in slots f, substantially as set forth.

2. In combination with a pair of hollow standards, a transverse knife or cutter having gudgeons provided with rounded heads, which slide up and down within said standards, the latter being provided with slots f to 90 allow the narrow parts of the gudgeons to move up and down, while preventing separation, substantially as set forth.

3. In combination with a pair of hollow standards having grooves or channels F, slots 95 f, and openings g, the transverse paper-cutter having gudgeons extending rearwardly from its ends and provided with rounded heads G and necks g', substantially as set forth.

4. In a paper-holder and device for cutting paper from rolls, the combination of a transverse cutter having gudgeons provided with rounded heads and narrower necks, with 100 standards having grooves adapted to receive

said heads and necks, the necks of said gudgeons being of sufficient length to allow the downward tilting of said cutter as the roll diminishes, for the purpose set forth.

5. In a paper-holder and device for cutting paper from rolls, the combination of a pair of standards with a transverse vertically-movable blade, said standards being provided with vertical grooves having a slot or narrow part f and enlargements g , arranged as shown, and

said cutter being provided with gudgeons which have rounded heads G and necks g' , substantially as set forth.

In testimony whereof I affix my signature in presence of two witnesses.

GEORGE E. YARGER.
